ATTORNEY

UNITED STATES PATENT OFFICE.

HENRY J. GRENIER, OF BRIDGEPORT, CONNECTICUT, ASSIGNOR OF ONE-HALF TO BELLE JACOBS, OF BRIDGEPORT, CONNECTICUT.

CUE TIP.

Application filed April 19, 1927. Serial No. 184,995.

My invention relates to a cue tip, and the invention has for its special object the provision of a novel means to securely fasten a cue tip in position.

5 The nature of my invention and its distinguishing features and advantages will clearly appear as the description proceeds.

Reference is to be had to the accompanying drawings forming a part of this specification, it being understood that the drawings 10 are merely illustrative of one example of the invention.

Figure 1 is a vertical section of a cue tip embodying my invention, showing the same 15 before the application of the leather or tip proper and showing a fragment of a cue in elevation.

Figure 2 is a view similar to Figure 1 but 20 with the leather secured in position.

Figure 3 is a section of the nut, table and 25 ring extending about the table.

Figure 4 is a plan view of the features shown in Figure 3.

Figure 5 is a side elevation of an element 30 having threaded engagement with the screw in securing the same within the cue sleeve.

Figure 6 is a plan view of the device shown in Figure 5.

In carrying out my invention in accordance with the illustrated example, the cue 10 is provided at the reduced forward end thereof with a sleeve 11 having externally the appearance of the ordinary sleeve. Said sleeve is formed with two diameters 13, 14, indicated at 12 and 13, the zone 12 of reduced diameter being internally threaded. On top of the tenon 110 on which the sleeve 11 is fitted is a disk 14 having a threaded nipple 15 rising therefrom at the center. The nipple 15 is adapted for fitted engagement with an internally threaded recess 16 formed in the lower end of a nut 17, the upper portion of which is solid above the recess 16 and is formed with a table 18 which has a bearing at its under side against the forward end surface of the sleeve 11.

Rising from the nut 17 above the table 18 is a stud 19 adapted to be upset, as herein-after described. Surrounding the table 18 is a fiber disk 20. The table 18 is rectangular or given other equivalent non-circular form, and in the disk 20 is a central opening of corresponding non-circular form. On the table 18 is placed a fastener crown 21 formed with a plurality of bendable fingers 22. The

base of the fastener 21 has slight depressions 23.

In practice the stud 19 is passed through the opening in the fastener 21 to be surrounded by the collar 23. The stud 19 is then upset, as shown in Figures 1 and 2, and the material thereof is crowded against the base of the fastener 21 and into the depressions 23. On the side of the disk 14 a plurality of spurs 24 is provided.

With the described arrangement the disk 14 is placed within the sleeve 11 to contact with the said sleeve at the shoulder produced by the zones 12, 13 of different diameters. The nut 17 is now screwed into place until the table 18 comes to a bearing against sleeve 11, in doing which the threads in the recess 16 will engage the threaded stud or nipple 15 so as to draw the disk 14 tightly against the shoulder referred to and cause the spurs 24 to penetrate the material of the sleeve 11 to prevent turning of the disk 14 and nut 17. The washer 20 is placed about the table 18 either before or after the screw 17 is applied to the cue. The fastener 21 is now passed onto the stud 19, and finally the leather 25 is placed against the forward ends of the fingers 22. Pressure is applied against the leather cap 25, causing the fingers 22 to penetrate the same. Said fingers 22 being bendable and slightly curved outwardly initially will be caused to penetrate the leather 25 and the fingers will be spread, thereby holding the said leather tightly in position. The crowding of the upset stud 19 into the depressions 23 prevents turning of fastener 21 and leather cap 25.

I would state furthermore that while the illustrated example constitutes a practical embodiment of my invention, I do not limit myself strictly to the exact details herein illustrated, since, manifestly, the same can be considerably varied without departure from the spirit of the invention as defined in the appended claims.

I claim:

1. A cue tip assemblage, including a sleeve formed internally with two zones of different diameters, the forward one threaded and the rear one the larger, an element accommodated within the sleeve at the forward end of the zone of larger diameter and having a threaded stud, a screw fitting the zone of the sleeve of smaller diameter and engaging the threads thereof, said screw hav-

ing a threaded recess at the inner end engageable by the stud of said element, a table on said screw presenting a non-circular outer edge, an element fitting about said 5 table and conforming to the non-circular formation thereof, a stud integral with the table and rising therefrom in the center, a fastener seated upon said table at the base of the stud rising therefrom and having an 10 opening through which said stud projects, and a cap, said fastener having bendable fingers and depressions at the base of the fingers at the front surface, said stud being upset and the material thereof entering said 15 depressions of the fastener and holding said fastener firmly in place, the fingers of the fastener penetrating the material of said cap.

2. A cue tip assemblage including a sleeve 20 formed internally of two zones of different diameters, one threaded, an element in the larger zone at the forward end, a member presenting a table and engaging said element, a disk conforming to the said table 25 and extending about the same, a cue cap, and means to fasten said cue cap to the table.

3. In a cue tip assemblage, a sleeve adapted to fit on the forward end of a cue, an ele-

ment in said sleeve at the forward end, a member presenting a table non-circular in form seated against the front end of said sleeve, means to hold said member to said element, and to the sleeve, a disk having a central opening conforming to said non-circular table, a cue cap, and means to fasten said cue cap to said table.

4. In a cue tip assemblage of the class described, a sleeve having internally two diameters, a disk fitting within the sleeve at the front end of the zone of larger diameter, a threaded stud on said disk, a screw having an internally threaded recess at the inner end engageable with said stud, a cue cap, and means to fasten the cue cap to said screw.

5. In a cue tip assemblage of the class described, a sleeve having internally two diameters, a disk fitting within the sleeve at the front end of the zone of larger diameter, a threaded stud on said disk, a screw having an internally threaded recess at the inner end engageable with said stud, a cue cap, and means to fasten the cue cap to said screw, said disk having spurs at the front side thereof penetrating the material of said sleeve.

HENRY J. GRENIER.
